CLAIM

The ornamental design for an electronic device charger with illumination, as shown and described.

DESCRIPTION

FIG. 1 is a rear perspective view of a first embodiment of an electronic device charger with illumination.

FIG. 2 is a front perspective view of the electronic device charger with illumination of FIG. 1.

FIG. 3 is a bottom view of the electronic device charger with illumination of FIG. 1.

FIG. 4 is a top view of the electronic device charger with illumination of FIG. 1.

FIG. 5 is a left side view of the electronic device charger with illumination of FIG. 1.

FIG. 6 is a right side view of the electronic device charger with illumination of FIG. 1.

FIG. 7 is a rear view of the electronic device charger with illumination of FIG. 1; and,

FIG. 8 is a front view of the electronic device charger with illumination of FIG. 1.

Broken lines in the Figures illustrate portions of the electronic device charger with illumination that form no part of the claimed design. Applicant hereby reserves the right to file one or more continuation applications claiming designs in which any one or more of the disclosed solid lines are broken and/or in which any one or more of the disclosed broken lines are solid.
